CHARLES M. MITSCHOW AND WILLIAM A. RAMEY, OF BUFFALO, NEW YORK.

ROTARY ENGINE.

1,219,837.

Specification of Letters Patent. Patented Mar. 20, 1917.

Application filed September 10, 1915. Serial No. 49,935.

To all whom it may concern:

Be it known that we, CHARLES M. MITSCHOW and WILLIAM A. RAMEY, citizens of the United States, residing at Buffalo, in 5 the county of Erie and State of New York, have invented new and useful Improvements in Rotary Engines, of which the following is a specification.

This invention relates to a rotary engine 10 which is adapted to be operated by a fluid under pressure such as steam. The objects of this invention are to provide the rotor of the engine with blades which are so constructed that the same are not liable to be 15 tipped by the pressure against the same and thereby enable these blades to slide freely and without undue wear; also to provide improved means for packing the joints between the outer edges of the blades and the 20 bore of the cylinder; also to provide improved means for packing the joint between the ends of the rotor and the ends of the cylinder; and also to provide simple and 25 efficient means for forcibly ejecting each blade on the inlet side of the cylinder by a companion blade which is on the outlet side of the same.

In the accompanying drawings: Figure 1 is a side elevation of a rotary engine embodying our improvements. Fig. 2 is a vertical longitudinal section of the same taken on line 2—2, Fig. 3. Fig. 3 is a vertical transverse section of the machine taken through the cylinder and rotor. Fig. 4 is 35 a vertical transverse section taken on line 4—4, Fig. 1. Fig. 5 is a fragmentary longitudinal section taken on line 5—5, Fig. 3. Figs. 6 and 7 are perspective views of one of the blades or pistons looking at opposite 40 sides of the same. Fig. 8 is an end view partly in section, on a reduced scale, of the rotor and the blades and end packing ring thereon.

Similar characters of reference indicate 45 corresponding parts throughout the several views.

1 represents the base or main frame of the engine which may be of any suitable construction. Upon the central part of this 50 base is mounted the cylinder or casing of the engine which comprises a cylindrical body 2 having its axis preferably arranged horizontally and provided with a cylindrical bore, and two heads 3 which close opposite 55 ends of the cylinder body and are detachably secured thereto by means of bolts 4 or

other suitable means. Along one longitudinal line or part of the bore of the cylinder, preferably the underside thereof, the same forms an abutment 5 and adjacent to one 60 side of this abutment the body of the cylinder is provided with an inlet 6 for the pressure medium and on the opposite side thereof the same is provided with an outlet 7 for the spent pressure medium. 65

Within the cylinder is arranged a cylindrical rotor 8 which rotates about an axis arranged on one side of or eccentric to the axis of the cylinder or casing, the axis of the rotor being such that a longitudinal part 70 of its periphery on the underside thereof engages with or is proximate to the abutment of the cylinder, as shown in Fig. 3, while its opposite ends engage with or are proximate to the heads or ends of the cylinder. 75 This rotor is rotatably supported in this position preferably by means of a shaft 9 extending axially through the same and turning therewith, the opposite ends of this shaft passing through stuffing boxes 10 arranged in the heads of the cylinder and journaled in bearings 11, 11 arranged externally of the engine cylinder. Each of these bearings is preferably constructed in the form of a sleeve and the same is adjustably supported so that the same can be 80 moved in all directions in a plane parallel with the direction of rotation for the purpose of relieving the stuffing boxes of the cylinder of undue wear as well as maintaining the rotor in its proper relation to the cylinder. For this purpose each of the bearings 11 is surrounded by the tubular head 12 of a standard 13 which rises from the base and the head is provided with a plurality of adjusting screws 14 which are arranged circumferentially on different parts thereof and engage with the outer side of the respective bearing. It will be apparent 85 from this construction that by suitably adjusting these screws the bearing sleeves can be shifted for bringing the same into the required position to properly support the shaft and the parts carried thereby. 90

In its periphery the rotor is provided with 105 a plurality of radial guide-ways 15 which, as shown in the drawings, are preferably four in number and are arranged equidistant circumferentially of the rotor but which number may be varied as desired. 110 Each of these guide-ways extends the full length of the rotor but terminates at its in-

ner end short of the axis of the rotor while its outer end opens to the periphery thereof. These guide-ways are preferably so arranged that the two on opposite sides of the 5 rotor are diametrically in line and together form a pair for purposes which will herein-after appear. Within each of these guide-ways is arranged a radially movable blade or piston 16 which is adapted to maintain its 10 outer edge in a definite relation to the bore of the cylinder whereby this blade is caused to move radially inwardly and outwardly relatively to the rotor as the blades and rotor turn together during the operation of 15 the engine. This is due to the fact that while the blade is passing over the abutment of the cylinder this blade is pushed inwardly to its maximum extent relative to the rotor, the blade then gradually moves outwardly 20 during the continued rotary motion in following the bore of this cylinder until it reaches a point on the latter diametrically opposite to the abutment, and then again gradually recedes into the rotor until the 25 abutment of the cylinder is reached. After the blade passes the pressure medium inlet on the intake side of the cylinder the pressure of this medium against the rear side of the blade pushes the latter forwardly and 30 after each blade during its forward movement passes the outlet for the spent pressure medium on the exhaust side of the engine the spent pressure medium between this blade and the next following blade escapes 35 through the outlet.

Although centrifugal force operates mainly to project the blades into their outermost position and hold the same in relation to the bore of the cylinder this action is supplemented and the engagement of the blades with the bore of the cylinder is rendered more certain, particularly when starting the 40 engine by means of spring pressure. For this purpose two springs 17 preferably of helical form are interposed between the inner edges of the two pistons of a pair which are arranged diametrically in line with each other on opposite sides of the axis of the rotor, the central parts of these springs being arranged in openings 18 extending from the inner end of one guide-way thereof to the inner end of the companion guide-way and also through the adjacent part of the engine shaft, as shown in Figs. 2 and 3.

55 When the engine has not been running for some time the blades are liable to stick in the guide-ways and not move out promptly on the intake side of the engine. To overcome this the blades of each pair are coupled in 60 such manner that the inward movement of each blade on the exhaust side operates to forcibly push its companion blade on the intake side outwardly relatively to the rotor. This is preferably accomplished by means of 65 two push rods 19 each of which is arranged

loosely within one of the helical springs 17 so as to serve as a guide for the latter and hold the same in place while its opposite ends are arranged loosely with pockets or recesses 20 in the inner ends of the companion blades. The length of each of these push rods is such that the same engages its opposite ends with the bottoms of the recesses or pockets 20 in the respective blades when the latter are arranged at right angles to a radial line drawn through the abutment of the cylinder and the axes of the cylinder and rotor, at which time these two blades approach each other most closely owing to the eccentric arrangement of the rotor within the cylinder. If there is any tendency of the blade on the intake side of the engine to stick the inward movement of the blade on the exhaust side of the engine will cause this movement to be transmitted through the 75 rods 19 to the corresponding blade on the intake side of the engine and push the latter outwardly so as to start the same after which the blade to be projected will continue its outward movement and maintain 80 its proper relation to the cylinder under the action of the push springs 17. After the push rods have performed this function of starting a blade outwardly on the intake side of the engine they simply operate as 85 guides for the push springs which are arranged around the same, this being due to the fact that the distance between the bottoms of the sockets 20 gradually becomes greater than the length of these rods up to 90 the time that each blade reaches a position diametrically opposite to the abutment of the cylinder after which the two blades of a pair again approach each other and the bottoms of their sockets 20 are again speared 95 a distance equal to the length of the push rods when the companion blades are arranged horizontally or at right angles to a radial line extending from the axis of the rotor to the abutment of the cylinder. This differential in the relative arrangement of the blades of each pair is due to the eccentric arrangement of the rotor within the cylinder which causes the distance between the outer ends of the blades when in a position at right angles to the abutment to be somewhat less than when these blades are arranged in line with the radius of the cylinder and the abutment.

Leakage of steam or other pressure medium from one compartment between adjacent blades of the periphery of the rotor to the compartments between other blades at the ends of the rotor and cylinder is prevented by packing devices each of which 100 preferably comprises a ring 21 arranged in an annular groove 22 in one end of the rotor and yieldingly held in contact with its outer side against the inner side of the adjacent cylinder head by means of a plurality of 105

5 springs 23. Each of the latter is arranged in a pocket 24 formed in the end of the rotor and opening at its outer end into the bottom of the adjacent groove 22, and each spring bearing at its inner end against the bottom of the companion pocket while its outer end bears against the inner side of the companion packing ring. Each of these packing rings is provided with a plurality of 10 radial slots or notches each of which receives the adjacent end of one of the blades, thereby enabling this packing ring to operate without interfering with the movement of the blades and also causing the blades to 15 form the means whereby the packing ring is turned with the rotor.

At its inner end each blade is provided with means for packing the joint between the same and the bore of the cylinder so as to produce a tight joint between 20 the same which will avoid leakage of the pressure medium past this joint. This packing preferably comprises a packing strip or bar 25 arranged with its inner side in a 25 longitudinal groove 26 formed in the outer end of the blade and bearing with its outer side against the bore of the cylinder. In order to enable this packing strip to shift its position and adapt its outer bearing surface 30 to the bore of the cylinder during the rotation of the rotor the inner side of this strip is made of arcuate form in cross section and the groove 26 is made of corresponding form in cross section. By this means the packing 35 strip is free to rock on the companion blade and adapt itself properly to the bore of the cylinder for maintaining a tight joint between the blade and the cylinder, thereby rendering it possible to obtain the maximum 40 efficiency of the pressure medium which operates against the rear side of the blade.

In order to counteract to some extent the centrifugal force whereby the several packing strips are pressed against the bore of the 45 cylinder during the operation of the engine and reduce the wear upon these parts accordingly means are provided which are preferably constructed as follows:

27, 27 represent openings extending from 50 the packing groove at the outer edge of each blade to the inner edge of the same. Within each of these openings is arranged a spring 28 preferably of helical form, which is secured at its outer end to the packing strip 55 mounted on the respective blade while its inner end is secured to a screw 29 which engages with the threaded inner part of the opening 27. By turning the screw so as to shift its position lengthwise in the respective opening the tension of the spring may be varied as required to off-set the centrifugal force whereby the packing strip is thrown outwardly against the bore of the cylinder and thereby insure a tight joint 60 between the blade and the cylinder without

undue wear of the cylinder and the packing strips. The springs 28 are able to perform the described function by reason of the fact that the blades are pressed laterally against the front sides of the radial guideways in 70 the rotor 8 by the pressure medium whereby the outward movement of the blades is frictionally retarded to a sufficient extent to serve as an anchor for the inner end of the springs and thus enable the same to modify 75 the outward pressure of the packing strips 25 under centrifugal action.

As the packing strips 25 are thrown outwardly by centrifugal force against the bore of the cylinder and the respective blades 16 are retarded in their outward movement by 80 reason of the steam pressure producing a binding or retarding effect between the blades and the rotor leakage between these strips and the blades is prevented by reason 85 of the packing strips being pushed laterally to a limited extent by the steam pressure so that the convex inner sides of the strips ride up on the convex outer ends of the blades with an edge like action and thereby serve 90 to close the joints between these strips and the blades which effectually prevents the passage of steam between the blades and the outer strips while the same are subjected to steam pressure. 95

In the absence of any provision to prevent it the pressure of the live steam or pressure medium against the rear side of each blade and the partly spent steam or pressure medium against the front side of the blade causes 100 an unevenness in this pressure whereby the blade is tipped or tilted and caused not only to slide hard in its guide-way but also to wear these parts unduly. For the purpose of avoiding this action each of the blades 105 is preferably constructed as follows:

On its rear side each of the blades is provided with a recess which terminates short of the outer and inner edges of the blade and which comprises a comparatively short or 110 small area outer part or section 32 which is arranged wholly on the outer part or half of the blade and a comparatively long or large area part or section 31 which is arranged wholly on the inner half or part of the blade. 115 On its front side each of the blades is provided with a recess 30 which is of comparatively long or large area and extends lengthwise of the blade but terminates short of its opposite transverse edges while its outer longitudinal side terminates short of the outer longitudinal edge of the blade and its inner longitudinal side is arranged about midway between the outer and inner edges of the blade, so that this recess is arranged wholly 120 on the outer part or half of the blade. 125

After each blade has effected the initial part of its outward motion relatively to the rotor and has passed the pressure medium inlet only the narrow outer part or section 32 130

of the recess on the rear side of the blade is exposed to the action of the live steam or pressure medium which permits this medium to pass inwardly to the enlarged inner section or part 31 of the rear recess and act with considerable pressure forwardly against the inner part of this blade at the same time that live steam is pressing forwardly against the unrecessed outer part of the rear side of this 5 blade, thereby equalizing to a certain extent the pressure of the pressure medium over the entire area of the rear side of the blade and reducing the tendency of this blade to tip or tilt in its guide-way. This tendency to tilt 10 the blade is further reduced after the blade has effected the initial part of its outward movement in the rotor and passed the inward port by reason of the outer part of the recess on the front side of the blade being at 15 this time exposed to the action of the partly spent steam or pressure in front of the same which medium is permitted to pass part way into engagement with the intermediate part 20 of the blade which is still covered by the guide-way and thereby distributes the pressure of this partly spent pressure medium more uniformly over the front side of this 25 blade. By thus modifying the effect of the live pressure medium on the rear side of each 30 blade and the effect of the partly spent pressure medium on the front side of the blade, the tendency of the blade to be tipped is reduced, thereby enabling the same to slide more freely and promptly in the rotor and 35 also reducing the wear on the co-operating surfaces of these parts, thereby reducing the friction in the engine and increasing its efficiency.

We claim as our invention:

40 1. A rotary engine comprising a cylinder having a longitudinal abutment on one part of its bore, an inlet for the pressure medium on one side of said abutment and an outlet for the spent pressure medium on the opposite side of said abutment, a rotor journaled

eccentrically in said cylinder so that one part of its periphery is proximate to said abutment and provided with a plurality of radial guideways, and a blade arranged in each of said guide-ways and movable radially therein relatively to the rotor and each blade provided on its rear side with a recess which terminates short of the inner and outer edges of said blade and which has a short outer part and a long inner part and each blade 50 being also provided on its front side with a recess which is arranged wholly on the outer part of the blade and extends lengthwise of the blade a greater distance than the short outer part of the recess on the rear side of 55 the blade.

2. A rotary engine comprising a cylinder having a longitudinal abutment on one part of its bore, an inlet for the pressure medium on one side of said abutment and an outlet 60 for the spent pressure on the opposite side of said abutment, a rotor journaled eccentrically in said cylinder so that one part of its periphery is proximate to said abutment and provided with a plurality of radial 65 guide-ways, a blade arranged in each of said guide-ways and movable radially therein relatively to the rotor and each blade provided in its outer edge with a longitudinal groove which is arcuate in cross section, a 70 packing strip arranged in each of said grooves and having an arcuate inner side engaging with the corresponding surface of said groove and engaging its outer side with the bore of said cylinder and means for counteracting the centrifugal action on said packing strip comprising a spring arranged 75 in a radial opening in said blade and connected at its outer end with said packing strip and means arranged in the inner end 80 of said opening and connected with the inner end of said spring.

CHARLES M. MITSCHOW.
WILLIAM A. RAMEY.
